UNITED STATES PATENT OFFICE.

FRANK HENDERSON, OF AUCKLAND, NEW ZEALAND.

HAT FASTENER.

1,403,118.

Specification of Letters Patent. Patented Jan. 10, 1922.

Application filed July 13, 1920. Serial No. 395,969.

To all whom it may concern:

Be it known that I, FRANK HENDERSON, a citizen of the Dominion of New Zealand, and a resident of Auckland, in the Provincial District of Auckland, in the Dominion of New Zealand, have invented certain new and useful Improvements in Hat Fasteners, of which the following is a specification.

This invention relates to devices used for 10 retaining hats on the heads of the wearers.

The object of the invention is to provide an improved form of fastener whereby hats are enabled to be securely held on the head, and to be easily removed therefrom when 15 desired, said fastener being also easily affixed to the hats and simply operated, besides which it is not unsightly and does not by its operation disfigure or damage the hats.

The fastener comprises a volute spring 20 provided with a stem extending from its coil of smallest diameter, said stem passing through the rear bar only of a pair of bars secured together at their ends, and being fitted with a detachable knob.

25 The bars are provided with eyes at the ends and between the latter are spaced a short distance apart.

In use the bars are attached to the inside 30 of a hat with the stem passing outwards through the latter.

On turning the stem in one direction the spring is screwed or wound into the space 35 between the bars and assumes the form of a coil spring, in which position it is completely disengaged from the hair, and on turning said stem in the reverse direction the spring is unwound or extended and screws itself into the hair.

In order that the invention may be more 40 clearly understood, it will be further described with the aid of the accompanying drawings, in which:—

Figure 1 illustrates how the device is used.

Figure 2 is an end view and

45 Figure 3 a side view of the device in the form it assumes when disengaged from the hair, while

Figure 4 is a side view of same extended or in the form it takes when engaged in 50 the hair.

Figure 5 is an enlarged side view and

Figure 6 is an enlarged side end view illustrating the fitting of the removable knob to the stem, and

55 Figure 7 shows the stem.

The device consists of a volute spring 1 of wire, having a stem 2 extending from its coil of smallest diameter. The stem 2 passes through the rear bar 3 only of two bars 3, 3^a secured together at the ends and 60 provided with eyes 4.

A knob 5 is detachably fitted on the outer end of the stem, which is flattened at 6, the latter portion being capable of being passed through the coils 8 of a small spring on 65 the knob 5 so as to enter the latter.

On the flattened portion 6 being forced into the coils 8 the latter expand sufficiently to allow said portion 6 to pass into the knob 5, after which the coils 8 contract around the 70 stem 2 and retain the knob 5 on the latter unless a tensional force is exerted on said knob. On turning the stem 2 in one direction the coils of the volute spring 1 are worked or screwed into and compressed in 75 the space between the bars 3, 3^a and said spring 1 takes the form of a coil spring.

When the stem 2 is turned in the reverse direction the outer end of the spring, which has a natural tendency to press outwards 80 in the direction of its axis passes on the outside of the bar 3^a, whereupon on the turning movement being continued the spring 1 is screwed or worked outwards and reassumes the volute form. During the latter operation the bar 3^a is disposed between 85 coils of the spring.

The device is secured to the inside of a hat by removing the knob 5 and passing the stem 2 through the hat from the inside, 90 and sewing the bars 3, 3^a to the hat through the eyes 4, after which the knob 5 is again placed on the end of the stem.

When placing the hat on the head, the 95 spring 1 is in its coiled or closed form as shown in Figure 3, so that by turning the stem 2 in the required direction said spring is caused to extend and at the same time screw or wind itself into the hair.

To unfasten the hat from the hair, the 100 spring 1 is withdrawn or unwound out of the hair into the space between the bars 3, 3^a as before described.

The device is used preferably at opposite 105 sides of the hat as shown in Figure 1.

What I do claim and desire to secure by Letters Patent of the United States is:—

A hat fastener comprising, a pair of parallel bars joined to each other and one of which is provided with eyes at its end; a 110

volute spring from the smallest diameter of which a stem with a flattened end passes through one of said bars; the other of said bars, when the spring is extended, being disposed between coils thereof; and a knob provided with coils to receive the flattened end of the stem.

In testimony whereof I have signed my name to this specification in the presence of two witnesses.

FRANK HENDERSON.
